UNITED STATES PATENT OFFICE.

PATRICK J. WHELAN, OF DOUGLAS, ONTARIO, CANADA.

BUTTON.

1,243,024.

Specification of Letter's Patent.

Patented Oct. 16, 1917.

Application filed February 14, 1917. Serial No. 148,575.

To all whom it may concern:

Be it known that I, PATRICK J. WHELAN, a subject of the King of Great Britain, and residing at Douglas, in the Province of Ontario and Dominion of Canada, have invented certain new and useful Improvements in Buttons, of which the following is a specification.

This invention relates to improvements 10 in buttons and the objects of the invention are to facilitate securing the button to a coat or other apparel of the wearer, to permit of the button face being automatically locked in position, to obviate any tendency 15 of the button face rotating or otherwise becoming displaced and generally to adapt the button to better perform the functions required of it.

With the above and other objects in view 20 the invention consist essentially of the improved construction particularly described and set forth in the following specification and accompanying drawings forming part of the same.

25 In the drawings,

Figure 1 is a perspective view of an improved button of the trouser type.

Fig. 2 is a vertical section of the same.

Fig. 3 is a perspective view of the rear 30 portion of the button.

Fig. 4 is a sectional view of the button face.

Fig. 5 is a perspective view of a button of the military, naval or police style.

35 Like characters of reference refer to like parts in all the figures.

Referring to the drawings A represents the improved button comprising the rear member 10 which is substantially disk shaped and provided with an orifice 11 therethrough, the outer portion of which is counter-sunk as shown at 12. Rotatably mounted in the orifices 11 is a screw 13 provided with a shoulder 14, which abuts 40 the inner face of the member 10, the outer end of the screw being provided with a tapered head and a slot 15 therein, thereby facilitating tightening the screw in a manner to be made clear hereafter.

45 The member 10 is also provided with a pair of guide pins 16 which are arranged in diametrically opposite sides of the screw 13 and are adapted to slidably engage with the orifices 17 provided in the button face

18 and located on diametrically opposite 55 sides of the threaded orifice 19 extending through the center of the button.

It will be understood that the pins 16 may be made with the slightest taper, so that when they are engaged with the orifices 60 17 they will frictionally engage with the same and permit of the screw 13 being tightened only to the desired extent.

The type of button shown in Fig. 5 is 65 essentially the same as that above described, the only difference being that the button face 18 is of a dome shape usually associated with military, police or other uniforms.

When the button is in use the article to 70 which it is to be attached is pierced to permit of the screw 13 passing therethrough whereby the pins 16 are pressed through the fabric and engaged with the orifices 17 in the button face 18. In this position it 75 will be understood the screw 13 engages with orifice 19 in the button face 18 and on the screw being turned with a small screw driver or the like the button face 18 is drawn tightly against the fabric of the 80 article to which the button is attached.

During this operation it will be appreciated that the button face 18 cannot rotate, that it is firmly held by the pins 16 while owing to the fact that these may be 85 slightly tapered the button face is only drawn up to the desired extent and there is no possibility of the fabric being chafed by the inner face of the button face 18 and the inner face of the member 10. 90

From this description it will be seen that I have invented a button that can be advantageously employed on wearing apparel of all descriptions such as ladies' suits, trousers, military and naval uniforms, police uniforms or as a badge or society button, the button being capable of being secured with a minimum of time and labor and when so positioned not distracting from the appearance of the wearing apparel 100 but rather adding to the same. 95

As many changes could be made to the construction and many apparently widely different embodiments of my invention within the scope of the claims constructed 105 without departing from the spirit or scope thereof, it is intended that all matter contained in the accompanying specification

2
and drawings shall be interpreted as illustrative and not in a limited sense.

What I claim as my invention is:

1. A button of the class described comprising a rear member, a button face, screw means operatively connecting the button face and the rear member and guide means carried by the rear member adapted to prevent rotation and displacement of the button face.

10 2. A button of the class described comprising a rear member, a button face, a screw rotatably mounted in the rear member and making threaded engagement with the button face and guide means carried by the rear member coacting with the button face.

15 3. A button of the class described comprising a rear member, a button face, a screw operatively connecting the button face to the rear member and pins located

on diametrically opposite sides of the screw coacting with the said button face.

4. A button of the class described comprising a rear member and an orifice there-through provided with a counter-sunk end, 25 a screw having a shoulder engaging with the inner face of the rear member and having a tapered head engaging with the counter-sunk end, a pair of pins located on diametrically opposite sides of the screw and 30 carried by the rear member and a button face making threaded engagement with the screw and slidably engaged with the said pins.

In witness whereof I have hereunto set 35 my hand in the presence of two witnesses.

PATRICK J. WHELAN.
